LOOSE LEAF BINDER

John Schade, Holyoke, Mass., assignor to National Blank Book Company, Holyoke, Mass., a corporation of Massachusetts

Application July 29, 1932, Serial No. 625,664

7 Claims. (Cl. 129—13)

This invention relates to an improvement in book binding structure, particularly an improvement in the telescoping type of loose leaf binders. In the first commercial embodiment that I have made, the invention is disclosed for use in a loose leaf book or binder in which the back portion is made up of two overlapping parts to make the telescoping type of binder.

I will point out the improvements in their various aspects by the claims defining the invention. But the general idea is to provide means at the back of a telescoping type book for loosening up the pages from a tightly bound condition to a loosely bound condition. Because of its compactness of design, as well as its flexible capacity, the telescoping type of binder has met with much favor but is open to the serious objection that because the sheets are ordinarily tightly clamped together with their bottom edges in one plane, it is very difficult to read the sheets close up to the binding post. Attempts to overcome this defect have been made by allowing an excessively wide margin between the post holes and the point where the reading matter starts. This, however, means an increase in the size of the book and the storage space required for same, as well as a waste of paper and binding material. By my invention one can open the book for reference and loosen the pressure of the binder on the sheets, thus facilitating the reading and individual handling of the pages. In its best form the loosening is accomplished automatically upon opening the book for reference and preferably by turning one of the covers to actuate the loosening mechanism. The tightly bound condition is desired for saving space and economy.

Referring to the drawing:

Fig. 1 shows an embodiment of the invention in loose leaf binder form with the pages in loose condition at the back. The view is from one end with the telescoped book opened out to reading position;

Fig. 2 shows an end view of the book in Fig. 1 but closed and the pages tightened up at the back for storage;

Fig. 3 is a top view of the binder arranged as in Fig. 2 but with the pages removed;

Fig. 4 is a detail view showing the two-part extensible back portions separated for clearness;

Fig. 5 is a detail view of the mechanism attached to the back of the binder for the purpose of controlling and manipulating the binder parts; and

Fig. 6 is a diagrammatic view to indicate the position of the cover that is connected with the

mechanism of Fig. 5 and when it is bent back as in Fig. 4.

Referring to Fig. 1, the book shown comprises the covers 1 and 4 hinged respectively to the overlapping back portions 2 and 3. The latter are provided inside the hinge lines with upstanding flanges 5 (on 2) and 6 (on 3). The flange 5 carries sheet or page binding posts 7 (see Fig. 4) and flange 6 carries offset posts 8. The latter have spring pressed (outwardly) extensions 9 while similar outwardly spring pressed extensions 7' are provided for posts 7. The book thus far described is of a usual telescoping kind in which punched pages are engaged by posts 7 and 8, the book closed to the position of Fig. 2 with back portions 2 and 3 overlapping. In this position it is customary to have some suitable means to lock the parts. And this is the position and condition in which the book is ordinarily handled for both storage and reference.

In such book constructions of the prior art, the object in making the back telescoping is to accommodate more or less sheets in the same binder and to also handle the sheets and binder conveniently in changing, filling, adding or subtracting sheets. In other words, it is for adjusting the size of the telescoping binder to the number of sheets bound and for transferring sheets to and from the binder.

To adapt such a book for my purpose and to show the principles of my invention I have provided the mechanism shown in Fig. 5. The part 10 is a flattened tube of sheet metal fastened to back portion 2 (see Fig. 4). Inside this part is pivoted a bell crank lever 11 with a tooth 12 at one end. This end is constantly pressed outwardly by a spring 13. The other end is engaged by a flange turned out of the plane of a flat link 14. The latter lies alongside of operating arm 15 but its flanged end turns over into the plane of 15 to engage the curved end portion of arm 15 for operating the bell crank lever 11 in opposition to the spring 13. All these parts operate inside the tube 10 which hides them, as indicated in Fig. 4, except for the outer end of link 14 and the tooth 12 (except when cover 1 is turned back to retract 12 as in Fig. 4). Tooth 12 can move out of the tube along one edge, as shown in Fig. 5.

A hinge plate 16 is riveted to cover 1 to turn with the cover at all times. This plate has a pintle engaging an eye at the end of link 14. Thus the turning of the cover 1 through the hinge pintle operates to move link 14 back and forth in tube 10 and as stated the link 14 operates

bell crank 11. The result is that the turning of the cover 1 and its position relative to back portion 2 determines the possible position of tooth 12 relative to the toothed stops 19 on bar 17. 5 Since cover 1 turns on the book cover hinge and plate 16 is pivoted to rod 14 on a line parallel but inside the cover hinge, it will be seen that link 14 will be moved inwardly of tube 10 when the cover 1 is closed. When it is opened to 10 reference position as shown in Fig. 1 it pulls link 14 outwardly to move tooth 12. And when it is moved still further open the tooth 12 is moved still further and finally moved inside of tube 10 as in Fig. 4. The reasons for these movements will 15 be explained.

The book parts are assembled by placing the pages on posts 7 and 8. Then the tube 10 is telescoped into flattened tube 18 (see Fig. 4). Tube 18 of sheet metal is fastened on the inside 20 of back portion 3. It has teeth along the edge adjacent to the side where tooth 12 is. In Fig. 5 this tube 18 is shown open at the bottom and part of tube 10 is cut away at the bottom. But Fig. 4 shows how these parts appear to the user. 25 If the cover 1 is in closed position with respect to back portion 2, link 14 is extended inwardly enough to let spring 13 press tooth 12 into ratchet engagement with teeth 19. Thus as the book parts are assembled in closed position with the 30 book covers pushing the pages for assembly on posts 7 and 9 from either one or both sides, the parts are locked. When the book is closed, it is desirable to have it closed and held closed in tightly packed condition of the pages. With 35 the structure shown, this can be done by pressing oppositely on the covers. The condition of Fig. 2 is thus brought about. It will be seen that such a condition of the structure shown requires plungers 9 to be received telescopically in posts 40 8 and plungers 7' similarly in posts 7. These posts have coiled springs inside (indicated by dotted lines in several of the posts) that are put under tension by the closing of the book to the condition of Fig. 2. These springs are 45 held under tension after the pressure on the book covers is released, since back portions 2 and 3 are held locked together by the tooth 12 engaging ratchet teeth 19. On account of the large number of ratchet teeth available for tooth 12 to engage, the book is adjustable with respect to 50 the number of pages it can hold. But the mechanism as I have arranged it is not primarily for giving adjustability of the book structure.

The mechanism of Fig. 6, without regard to 55 adjusting the book parts for more or less pages, is primarily arranged to have the book closed tightly as in Fig. 2, and in addition to have the book open for reference, as in Fig. 1. In the latter position the back is expanded so as to 60 permit the pages to lie out in a flatter curve than they could lie out if the back were kept in the condition of Fig. 2. This will be clear from Fig. 1. Each page can be spread out and examined from the line of its attachment to the back outwardly and without difficulty, no 65 matter how close the inner margin of the printing may be to the said line of attachment. Every one knows from experience how awkward and difficult it is to use the common form of thick book in which the back holds the leaves near the inner margin of the printing at a steep angle when the book is open. This condition has made the use of telescoping loose leaf binders in thick 70 form especially difficult. It can be solved by leaving a large enough blank margin on the inner

side of the printed page so that the printed part starts on a flat enough curve for easy reference. But this requires excess material in the area of the binder, the page contents, and more space for storing the book, all of which is so highly objectionable that the tendency has been in adjustable loose leaf binders to leave the difficulty in the construction of the ordinary thick book for the reader to meet as best he can.

In my construction, when the user opens the closed book the cover 1 operates link 14 to pull tooth 12 out of line with ratchet teeth 19, as indicated in Fig. 5. This is the position of the parts when cover 1 is parallel to back portions 2 and 3, as in Fig. 1. In such position, tooth 12 is in line with stop 20 arranged at the outer end of ratchet teeth 19, see Fig. 5. Cover 1 and back portion 2 can now be separated from cover 4 and back portion 3 until tooth 12 abuts stop 20 in the separating movement. The distance of separation is that between the ratchet tooth engaged by tooth 12 when the book is tightly compacted with the covers the minimum possible distance apart considering the contents and the stop 20. If this movement of the back were for the mere adjustability of the book contents there would be no reading advantage possible in the structure when the contents were at their maximum. At this point is where the reading advantage is most needed. So it will be seen that my increase of 100 the width of the back portion is an increase beyond and in addition to any variation of width that may be provided for varying the book contents. The stop 20 for tooth 12 keeps the book covers from separating more than desirable for 105 my purpose of rendering an easy reference position or exposure of the pages. The latter are as effectively bound on the back between the covers in their position of Fig. 1 as they are in that of Fig. 2.

I can operate the book by moving it between these two positions by hand, including a hand operation for separating back portions 2 and 3 until stop 20 is engaged by tooth 12. But there is considerable advantage in rendering the last 120 operation automatic. I have done this by providing the spring pressed extensions 9 telescoping with posts 8 (see Fig. 4). When the book is closed, as in Fig. 2, the extensions 9 are retracted against their springs and constantly press outwardly against flange 5, thus tending to separate the back portions. Like spring pressed extensions 7' are provided on the opposite side. Tooth 12 prevents action until cover 1 is opened. Then the springs can act and spring extensions 9 and 130 7' throw the back parts automatically to the position of Fig. 1. But the closing of the book is by hand pressure against the cover 1 or both covers so as to cause part 10 to telescope in with part 18 and for tooth 12 to ratchet on teeth 19 135 to hold the book tightly bound, as already stated.

The action in my commercial form chosen for illustration is smooth and easy, requiring no bother on the part of the user. All he needs to do is open the book and it automatically 140 loosens up the back to make his reading easy. In closing the book it is obvious that it has been expanded and a slight hand pressure by the user soon becomes instinctive as part of the closing operation to contract the back for storage. 145 Whenever it is desired to take the book apart for changing sheets, it can be done as follows: The cover 1 is bent back from the position of Fig. 1 toward a right angle position with back portion 2, as in Figs. 4 and 6. This draws link 14 (Fig. 5) 150

further out of tube 10, operating to further move bell crank 11 against spring 13 and until tooth 12 is drawn in out of line with stop 20. Then portions 1 and 2 can be fully separated from portions 3 and 4 and either pair can carry all or part of the pages.

The book as shown, has all the advantages of a loose leaf book of the extensible type. Part of its structure suggests the purpose of an expandible back for varying contents. But the main plan of the invention is something different; it is to make the book easier to read. Many publishers want a loose leaf book for the purpose of partially changing portions of its contents, to which the expansible type of book is particularly adapted, to keep the book up to date by periodical distribution of the revisions on loose leaf sheets. The thickness of such books varies from time to time. Posts 7 on one side or posts 9 on the other side can hold the entire volume of reference pages on the one cover or part on one and part on the other, flanges 5 and 6 acting as transfer bars in the sense that a part of the contents can be mounted on the bar on one-half of the binder, which half can then be separated with its bar holding such contents which can be transferred for assembly with the other half of the binder and its part of the contents when the whole is reassembled. This method of handling pages for substitution at the right place in the volume is pretty well known. It is particularly desired by the publishers and users. I wish to point out how effectively I have added the feature of my invention to such a book. The mechanism of Fig. 5 not only locks the loose leaf book in assembled position but by the addition of one or two simple parts to the parts needed for mere locking I have provided the new feature to make the book easy to read. Because it is easy to read, such a book can now be put out whenever desirable, in thicker form than has heretofore been practical. But in any thickness such a book is a more conveniently used article.

Other types of holding means operable by the cover can be readily substituted for the preferred form shown. I intend to claim the invention in its broad as well as in its specific aspects.

What I claim is:

1. A book comprising, a back having expandible and contractible overlapping portions, covers hinged thereto, page holding posts extending above and across the back, mechanism having a part on one and a part on the other of said overlapping portions, engageable and releasable to bind and release said overlapping portions for expansion and contraction according to the position of said mechanism parts, and a mechanical connection between one of said parts and one of the hinged covers to determine the relative position of such parts by the position of the cover, said cover placing said parts of the book back in position for expansion of the back only when the covers are opened for reference condition of the book and a stop forming part of said mechanism to limit such expansion and keep the pages bound in the book, whereby the book may be held contracted when closed or expanded with the pages bound loosely enough for easy spreading to good reference position when the book is open.

2. A loose leaf binder comprising an expandible back having loose leaf structure mounted thereon with spring pressed posts to hold pages, covers hinged to said back, said posts normally acting to expand the back and positioning mechanism on

said back operable by connection with one of the covers to prevent back expansion when the cover is closed against the book contents and releasable to permit back expansion when said cover is opened to lie parallel to the back, said mechanism also providing a stop to prevent complete separation of the back parts until the said cover is turned beyond its position parallel to said back.

3. A loose leaf book of the type arranged for expanding and contracting the width at the back of the binder comprising in combination two covers, two overlapping back portions hinged to the covers and each carrying loose leaf structure including sheet holding posts extending above and across the back of the book, two cooperating stop members, one carried on one back portion and one on the other back portion, said stop members being normally in position when the covers are opened for reading to permit and limit the separation of the back portions substantially to the position for their greatest cooperative expanded condition while holding book sheets in bound form, said stop members at all times permitting free sliding of the back members to their smallest cooperative contracted condition, one of said stop members being movable out of cooperating position with respect to the other, mechanism permanently mounted on the book and operatively connected to one of the covers to move such stop members into and out of such cooperating position, said combination being constructed to bind a full book of sheets having the thickness of the binder in fully contracted condition and permitting easy and convenient loosening of the sheets at the back of the book for reading in that condition of the book when the back is fully expanded.

4. The combination of claim 3 with means operable to lock the book back in fully contracted position when the covers are closed.

5. The combination of claim 3 with a ratchet bar, said permanently mounted mechanism being operable by one of the covers upon closing to put one of said stops in position to cooperate with said bar and lock the book back against any expanding movement.

6. The combination of claim 3 and automatic actuating means operable when the book is opened to reading position to expand the width of the book back until the cooperating stops are engaged one with the other.

7. In a book construction for the purpose described a book part positioning mechanism comprising two telescoping hollow members for attachment to opposite overlapping back portions of the book, a ratchet and end stop in one member, a cooperating spring pressed pawl in the other member having a tooth adapted to extend beyond its containing member into engagement with said ratchet teeth or stop, a linkage means connected to operate the pawl and extending into said pawl containing member, said linkage means extending out of the container with a part for attachment to and operation by a cover of the book in turning to open and closed position, said linkage, pawl, ratchet, and stop being arranged for the turning of the connected cover to engage the pawl and ratchet when the cover is closed, to take the pawl out of line with the ratchet teeth and into line with said stop when the cover is open to reading position, to take the pawl out of line with said stop when the cover is opened beyond reading position.
